NOZZLE UNIT FOR SWIMMING POOL VACUUM CLEANERS

Abraham Berg, 9 Ingram Drive, and William Bouwmeester, 5 Juniper St., both of Hicksville, N.Y.

Filed Jan. 9, 1958, Ser. No. 49,178

Term of patent 7 years

(Cl. D9—2)

Fig. 1 is a side elevation of a nozzle unit for swimming pool vacuum cleaner embodying a new design;

Fig. 2 is a rear view; and

Fig. 3 is a top plan view thereof.

We claim:

The ornamental design for a nozzle unit for swimming pool vacuum cleaners, substantially as shown.
